INVENTOR:

Frederick L. McGahan,
BY
Hugold S. Wagner,
ATTORNEY.

UNITED STATES PATENT OFFICE.

FREDERICK L. McGAHAN, OF LOS ANGELES, CALIFORNIA; VIOLA K. WALKER, ADMINISTRATRIX OF SAID FREDERICK L. McGAHAN, DECEASED, ASSIGNOR TO THE PURPOSED MIND DEVELOPMENT SECURITY ASSOCIATION OF THE WORLD, A TRUST COMPANY.

FIRE BOX.

1,423,347.

Specification of Letters Patent. Patented July 18, 1922.

Original application filed January 3, 1918, Serial No. 210,146. Patent No. 1,292,399, dated January 21, 1919. Divided and this application filed January 17, 1919. Serial No. 271,716.

To all whom it may concern:

Be it known that I, FREDERICK L. McGAHAN, a citizen of the United States, residing at the city of Los Angeles, in the county of Los Angeles and State of California, have invented certain new and useful Improvements in Fire Boxes, of which the following is a specification.

This application is a division from the application of the same inventor for patent for locomotive filed January 3, 1918, Serial 210,146, which became Patent 1,292,399, Jan. 21, 1919, and relates more particularly to an alternative form of construction of fire-box with arch therein.

In the accompanying drawings forming part of this specification, in which like numbers of reference denote like parts wherever they occur,

20 Figure 1 is a sectional view showing the construction of the fire-box and the location of the nozzle inlets thereinto for powdered fuel, this section being taken substantially on the line 1—1 in Figure 2;

25 Figure 2 is a fragmentary side elevation of an engine cab showing the furnace wall and fire-box in section, and the fuel feed partially in side elevation.

The fire-box 52 is located in the usual relation to the cab 2, and fuel, preferably pulverized, is normally fed to the fire-box 52 by a mechanical stoker consisting of the endless screws or other suitable force-feed 3, their flexible joints 4 and pipes 5 telescoping with 35 inlet pipes 6 which communicates with nozzles 7. It is to be understood that parts numbered respectively from 3 to 7, both inclusive, are duplicated upon the opposite sides of the engine cab. Thus the fuel is fed into 40 fire-box 52 out of nozzles 7 located respectively on both sides of the fire-box 52.

Inlet pipes 6 lead to nozzles 7, and at their other ends telescope pipes 5, which, by flexible joints 4, communicate with the source 45 of powdered fuel supply 8. Thus screw 3 forces the powdered fuel through joints 4, pipes 5 and 6, and nozzles 7 into the fire-box 52. The usual crown sheet 1 is provided.

The fire-box 52 is provided with the usual 50 grate-bars 9 and fire tubes 10 associated with the tube sheet 14.

Water tubes 11 support fire-brick arch 12 which partitions the fire box off into commu-

nicating chambers. It will be observed that the tubes 11, extending diagonally from the 55 rear wall of the fire box upwardly to the front wall of the fire box and that the fire brick 12 are arranged to only permit communication between the chambers of the fire box at the upper end of said water tubes 11, 60 which is at the end of the partition or arch 12, furthest from the fire tubes 10.

The powdered fuel entering through nozzles 7, oppositely located and adapted to discharge toward each other from opposite 65 sides of the fire-box 52, meets at the ignition-point 13 in the fire-box underneath the arch 12. Combustion there occurring, the flames break over the top of the arch 12, following the course indicated by the arrow in Figure 70 2, to reach the fire-tubes 10.

By the use of powdered fuel and this arrangement of the fire-box, the advantage results that combustion instantly occurs upon the introduction of fresh particles of fuel 75 into the fire-box 52. The fact that the fuel is in a finely comminuted state also facilitates combustion. The entrance of fuel into the fire-box and the exit of the products of combustion therefrom through the fire tubes 80 are facilitated by the action of any suitable suction means in proper relations with the discharge ends of said tubes.

It may be stated that the force-feed screw 3, may be continuously operated. Thus continuous feeding of the powdered fuel is produced, which is preferable to the interrupted or spasmodic firing by firemen, as it results in greater certainty and regularity of fuel supply, which is necessary for a regular and reliable head of steam. More complete combustion of the fuel is obtained by this apparatus.

Having thus described this invention, I hereby reserve the benefit of all changes in 95 form, arrangement, order, or use of parts, as it is evident that many minor changes may be made therein without departing from the spirit of this invention or the scope of the following claim.

I claim—

In a boiler, the combination of a fire-box having end and side walls, substantially horizontal fire tubes leading from one of the end walls, water tubes within the fire-box and extending diagonally from one end wall at a

point below said fire tubes upwardly to the other end wall, at a point near its top, refractory material overlying and supported by said water tubes forming a partition dividing the fire box into two chambers communicating at the end of partition remote from the fire tubes only, and fuel discharging nozzles leading into the side walls of the fire-box and in substantial alinement to discharge the fuel delivered there-through

toward each other, the point of ignition being at the center of the fire-box below said partition, means for creating a draft through the fire-box whereby the products of combustion traverse the chambers and exit 15 through the said fire tubes.

In testimony whereof I hereunto affix my signature.

FREDERICK L. McGAHAN.
